UNITED STATES PATENT OFFICE.

CHARLES F. OBERECHT, OF BALTIMORE, MARYLAND.

VALVE.

No. 867,405.

Specification of Letters Patent.

Patented Oct. 1, 1907.

Application filed February 9, 1907. Serial No. 356,505.

To all whom it may concern:

Be it known that I, CHARLES F. OBERECHT, a citizen of the United States, residing at Baltimore city and State of Maryland, have invented certain new and useful Improvements in Valves, of which the following is a specification.

My invention relates to an improvement in globe valves and the like, the object being to provide a valve whereby the life as to the use thereof may be prolonged and at the same time I have provided a valve with an adjustable and reversible as well as a removable seat, it may therefore be adjusted at the seat to meet whatever requirements are necessary to insure a closure against various pressures; and again I have constructed this valve so that when it becomes worn out and rendered useless, by reason of the seat having worn out that a new seat can be replaced therein without dispensing with the entire valve, thus rendering a saving to the user, as the seat can be replaced at a comparatively small cost as compared with an entire new valve, and it is a well known fact that the seat of a valve is the part which usually wears out first. By the use of my device the life of the valve proper is, to a considerable extent, prolonged.

My invention further consists in certain new and novel features of construction and combinations of parts which will be hereinafter described and pointed out in the claims.

Referring to the drawings, Figure 1, is a vertical central section through the valve and casing, the valve stem being shown seated on the adjustable valve seat; Fig. 2, is a detail view of the valve seat.

A, is the body portion made of any suitable material (preferably brass); 1 is an inlet and 2 an outlet. 3 is a bonnet secured to the body portion A by means of the bolts 4 and nuts 5, secured on the bonnet by similar means, viz: bolts 6 and nuts 7 to a gland 8; 9 is a spindle threaded at 10; 11 is a wheel secured on the upper end of the spindle 9; 12 is the valve disk; 13 is the collar; 14—14 are valve seats on the collar and 15 are lugs on the collar for the purpose of facilitating the removal and adjustment of the said collar and the seating of the valve seat; the collar 13 is inwardly threaded at 16 for the purpose of being engaged by the threaded body portion 17; the threads 10 on the spindle 9 are cut contrary to those of 17 on which the collar 13 screws or vice versa that the collar 13 may not have a tendency to become unscrewed by the valve disk being tightly

screwed down upon it, for this reason the threads on one should be directly opposite of those on the other. 50

It will be noted that I have provided a seat 14 on the top and also one on the bottom of the collar so that when one seat becomes worn the collar may be reversed thereby supplying a new seat.

Slight changes might be resorted to in the form and arrangement of the several parts described without departing from the spirit and scope of my invention, hence I do not desire to limit myself to the exact construction as herein set forth; but,

Having described my invention what I claim as new 60 and desire to secure by Letters Patent, is:

1. The combination in a valve of the character described, comprising a body portion provided with an inlet and outlet therein, of a bonnet secured on the body portion, a gland secured within the bonnet, a spindle provided with a wheel on the upper end thereof, the said spindle being extended through the bonnet and the said gland secured thereinto, the lower end portion of the said spindle being screw threaded and provided with a valve disk secured on the end thereof, an interiorly threaded collar, lugs exteriorly provided on the said collar, valve seats formed on the upper and lower edges of the said collar, an internal threaded body portion upon which the said collar is secured, the threads on the said internal body portion being oppositely disposed from those on the end of the spindle 75 upon which the valve disk is secured, substantially as described.

2. The combination in a valve of the character described, comprising a body portion and a collar, of a valve seat formed on the upper and lower edges of the said collar, 80 lugs exteriorly provided on the collar, screw threads inwardly provided within the said collar, an internal threaded body portion upon which the said collar is secured, a screw threaded spindle provided with a valve disk on the lower end thereof, the threads on the spindle being oppositely disposed from those on the said internal body portion 85 and within the said collar, substantially as described.

3. The combination in a valve of the character described, and a collar, of valve seats provided on the upper and lower edges of the said collar, screw threads inwardly provided within the said collar, a threaded valve stem, a valve disk secured on the lower end of the said valve stem, the said threads on the valve stem being oppositely disposed from those within the said collar, lugs exteriorly provided on the said collar for the purpose of adjustment and removal, substantially as described. 95

In testimony whereof I affix my signature in presence of two witnesses.

CHARLES F. OBERECHT.
